RADIATOR SHELL

Filed Oct. 29, 1928

INVENTOR.
Joseph. Etrych.

BY

Thos. Donnelly
ATTORNEY.

UNITED STATES PATENT OFFICE.

JOSEPH ETRYCH, OF DETROIT, MICHIGAN.

DESIGN FOR A RADIATOR SHELL.

Application filed October 29, 1928. Serial No. 28,688. Term of patent 3½ years.

To all whom it may concern:

Be it known that I, JOSEPH ETRYCH, a citizen of the United States, residing at Detroit, in the county of Wayne and State of Michigan, have invented a new, original, and ornamental Design for a Radiator Shell, of which the following is a specification, reference being had to the accompanying drawing, forming a part hereof, and in which—

Fig. 1 illustrates the invention in front elevation. Fig. 2 is a sectional view taken on line 2—2 of Fig. 1.

I claim:

The ornamental design for a radiator shell, as shown.

JOSEPH ETRYCH.
